UNITED STATES PATENT OFFICE.

PAUL ROHDE, OF WAIDMANNSLUST, GERMANY, ASSIGNOR TO GENERAL ELECTRIC COMPANY, A CORPORATION OF NEW YORK.

AUTOMATIC STARTING DEVICE FOR ELECTRIC MOTORS.

Application filed March 14, 1924. Serial No. 699,291.

To all whom it may concern:

Be it known that I, PAUL ROHDE, a citizen of Germany, residing at Waidmannslust, Germany, have invented certain new and useful Improvements in Automatic Starting Devices for Electric Motors, of which the following is a specification.

My invention relates to dynamo electric machines and particularly to automatic starting devices for such machines.

Automatic starting devices which operate in response to centrifugal force to cut-out resistances have been used to some extent in the past. These devices have been, in most cases, mounted on the shaft of the electric motor and as the speed of the motor increases operate to cut-out resistance step by step. With this type of device special disconnecting contacts are required for cutting out different sections of the resistance. Such an arrangement is open to the objection that as the resistance is cut-out step by step sparks will form between the contacts and so oxidize them that their conductivity and successful operation will be impaired. Another objection to such a device is the dangers attendant on the formation of sparks in dynamo electric machines.

The object of the present invention is to provide a device which will overcome the above objections, be cheap, simple in construction and render the use of special cutting-out contacts unnecessary.

In carrying out my invention I mount a circular resistance element and a resistance short-circuiting means on the rotatable member and arrange the resistance element and the short-circuiting means relatively eccentric with reference to the axis of rotation of the rotatable member so that the resistance will be progressively short-circuited as the speed of the rotatable member increases.

For a better understanding of my invention reference may be had to the following descriptions taken in connection with the accompanying drawing in which Fig. 1 is an end elevation partly in section of a starting device built in accordance with my invention, and Fig. 2 is a sectional view taken along the line 2—2 of Fig. 1.

In the accompanying drawing, a casing 10 is shown mounted upon a shaft 11 adapted to rotate therewith. Mounted eccentrically within the casing 10 is a substantially circular helical resistance element 12 and adja-

cent to, and outside of the helical resistance element 12 are two concentrically arranged semicircular members 13 which are adapted to progressively short-circuit the helical resistance element 12 as it is thrown outwardly due to centrifugal force as the speed of the rotatable member increases. The ends of the helical resistance element 12 are carried through the casing 10 and are provided with terminal connections 14. Equally spaced about the casing 10 and within the circular resistance element 12 are located insulating rollers 15 which support the helical resistance element 12. These insulating rollers 15 are mounted upon rods 16 which are adapted to move radially within elongated slots 17 formed in the side of the casing 10. The slots 17 are of different lengths, their outer ends being located on a line concentric with the axis of rotation and the inner ends being located along a line eccentric with the axis of rotation. The slots 17 are arranged radially with respect to the shaft 11 so that the insulating rollers 15 can move outwardly and maintain contact with the helical resistance element 12 as it moves outwardly due to centrifugal action. These insulating members, because of their weight, also act to cause the helical resistance element 12 to move outwardly. The weight of the rollers 15 can be varied to produce different degrees of sensitiveness or additional weights might be added at the ends of the rods 16. In some cases the rollers 15 may be fixed, and the resistance element 12 alone allowed to move outwardly by reason of its own weight and centrifugal force. In operation, the centrifugal force exerted upon the helical resistance element 12 and the rollers 15 due to the speed of the rotatable member will cause the circular resistance to expand and engage the semi-circular members 13. This construction produces a gradual rolling of the resistance coils into contact with the short-circuiting members 13 which are arranged adjacent thereto. The expansion of the circular resistance results in progressively cutting-out the resistance since the successive portions of the resistance gradually and progressively press against the contact plates and thus produce an increasing short-circuiting of the helical turns along themselves. The return of the helical turns of the expandable resistance into their original position as the centrifugal force decreases is

caused either by their own elasticity or by any suitable spring action which might be provided.

In Fig. 2, there are shown two helical resistance elements 12, one for each phase of a two phase induction motor of the wound rotor type. I desire to have it understood, however, that any number of helical resistance elements might be provided depending upon the particular application and the number of phases of the motor. It should also be understood that the helical resistance elements can be arranged concentric and the short-circuiting means eccentric with the axis of rotation and that many other modifications might be made without departing from the spirit and scope of my invention.

What I claim as new and desire to secure by Letters Patent of the United States, is:

1. In a dynamo electric machine, a rotatable member, a starting device on said rotatable member comprising a substantially circular resistance element surrounding said rotatable member, and a substantially circular short circuiting element surrounding said rotatable member and normally eccentrically arranged with reference to said current resistance element, the inner one of said elements being expansible and supported to permit engagement with the outer member for progressively short-circuiting portions of said resistance element as the speed of said rotatable member increases.

2. In a dynamo electric machine, a rotatable member, a starting device on said member comprising an expansible substantially circular resistance element movably supported around said rotatable member and eccentrically arranged with reference to the axis of rotation of said rotatable member, and means for progressively short-circuiting portions of said resistance element as the said resistance element expands when the speed of said rotatable member increases.

3. In a dynamo electric machine, a rotatable member, a starting device on said member comprising a helical resistance element movably supported around said rotatable member and eccentrically arranged with reference to the axis of rotation of said rotatable member, and means for progressively short-circuiting portions of said resistance element as the speed of said rotatable member increases.

50
55
5. In a dynamo electric machine, a rotatable member comprising a helical resistance element movably supported in substantially circular form around said rotatable member, and a substantially circular contact member surrounding said resistance element and supported eccentrically thereto for progressively short-circuiting portions of said helical resistance element as the speed of said rotatable member increases.

60
65
6. In a dynamo electric machine, a rotatable member, a starting device on said member comprising an expansible substantially circular resistance element surrounding said rotatable member, movable supports for said resistance element adapted to move radially with said element as the speed of said rotatable member increases, and a substantially circular contact member surrounding said resistance element and supported eccentrically thereto for progressively short-circuiting portions of said resistance element upon the expansion of said circular resistance element.

70
75
7. In a dynamo electric machine, a rotatable member having radial slots of different relative lengths formed therein, a starting device on said member comprising an expansible substantially circular resistance element eccentrically arranged with reference to the axis of rotation of said rotatable member, movable weights for supporting said resistance element mounted within said slots and adapted to move radially with and expand said resistance element as the speed of 80 said rotatable member increases a substantially circular contact member surrounding said resistance element and supported eccentrically thereto for progressively short circuiting portions of said element upon the 85 expansion thereof.

In witness whereof, I have hereunto set my hand this 21st day of February 1924.

PAUL ROHDE.
